UNITED STATES PATENT OFFICE.

CYRUS ROBINSON, OF NEW YORK, N. Y., ASSIGNOR TO WESTINGHOUSE MACHINE COMPANY, A CORPORATION OF PENNSYLVANIA.

SPEED-GOVERNOR.

SPECIFICATION forming part of Letters Patent No. 758,020, dated April 19, 1904.

Original application filed June 28, 1900, Serial No. 22,004. Divided and this application filed September 3, 1902. Serial No. 121,937. (No model.)

To all whom it may concern:

Be it known that I, CYRUS ROBINSON, a subject of the King of Great Britain, residing in New York, in the county of New York and 5 State of New York, have invented a new and useful Improvement in Speed-Governors, of which the following is a specification, this application being a division of my application, Serial No. 22,004, filed June 28, 1900.

10 My invention relates to retarding devices which severally embody a cylinder, a piston, a piston-rod, and some fluid in the cylinder against which the piston acts and by which its movement is resisted and retarded.

15 The object of my invention is to provide a device of the character above indicated which shall be simple and comparatively inexpensive in construction and effective in operation and which shall be specially adapted for automatic 20 adjustment to different degrees of movement of the mechanism or element to which it is attached.

25 My invention is primarily designed for use in connection with governors of steam-engines; but since it is not restricted to that specific use it is shown detached and will be described and claimed as of general application.

The invention is illustrated in the accompanying drawings, in which—

30 Figure 1 is a longitudinal sectional view thereof, a portion of the piston-rod being broken away; and Fig. 2 is a transverse sectional view on line II II of Fig. 1.

35 The cylinder 1 is provided with a removable head 2 at one end, having a screw-threaded socket 2^a to receive a supporting screw-stud. Adjacent to the removable head 2 is a port 3, that opens into a by-pass 4, which extends 40 longitudinally through the side wall of the cylinder and has at its other end a port 5 opening into a valve-chamber 7, formed in the head 1^a of the cylinder. The by-pass has also a smaller port 6, that opens into the cylinder at 45 a point adjacent to the head 1^a. A passage 8 leads from the valve-chamber 7 to the interior of the cylinder, and this passage and the port 5 are normally closed by means of a valve 9, which is normally held to its seat by means of

a coil-spring 10 and a cylindrical cap 11, that fits over the spring and has a screw-threaded engagement with the walls of the valve-chamber 7, so that the pressure exerted by the spring may be varied by screwing the cap 11 inwardly or outwardly. The cap 11 is provided with a lock-washer 12, having a handle 13. The port 6 is provided with a screw-valve 14, which may be turned by means of a thumb-nut 15 to vary the effective size of the port. This valve is also provided with a lock-washer 16, having a handle 17. As the piston 18 is moved backward and forward in the cylinder by means of the piston-rod 19 it will obviously force the fluid through the by-pass in the one direction or the other in accordance 65 with the direction of the movement of the piston.

In case this device is employed in connection with an engine-governor the port 6 will provide a sufficient opening for the passage 70 of the fluid under all slight fluctuations in engine-speed on account of small changes in load; but if there are large changes in load and speed the liquid-pressure may become sufficient to raise the valve 9, and thus provide 75 for a greater flow of fluid, and consequently a more rapid movement of the speed-governor piston.

The details of construction may obviously 80 be varied from what is shown and described without departing from my invention, and I therefore desire it to be understood that limitations are not to be imposed except by what is found in the prior art.

I claim as my invention—

1. A speed-governor comprising a cylinder and a piston, and having a by-pass around the piston and two ports opening into the by-pass from the cylinder, said ports being respectively provided with an automatic valve and a non-automatic valve.

2. A speed-governor comprising a cylinder and a piston, and having a by-pass around the piston and two ports of unequal size opening into said by-pass from the cylinder, said ports being respectively provided with an automatic valve and a non-automatic valve.

3. A speed-governor comprising a cylinder

85

95

and a piston, and having a by-pass around the piston and two ports of unequal size opening into the cylinder, the larger port having an automatically-operating valve and the smaller port having a non-automatic valve.

4. A speed-governor comprising a cylinder and a piston, and having a by-pass around the piston and two ports of unequal size, the larger port having an automatic valve and the smaller port having a non-automatic valve.

5. A speed-governor comprising a cylinder and a piston, and having a by-pass around the piston and two ports between the cylinder and the by-pass, one of said ports being provided with a manually-operated adjusting-valve and the other being provided with a spring-seated automatic valve.

6. A speed-governor comprising a cylinder and a piston, and having a by-pass around the piston and two ports of unequal size opening into the by-pass from one end of the cylinder, a spring-seated valve for the larger port and

a manually-adjustable, non-automatic valve for the smaller port.

7. A speed-governor comprising a cylinder and a piston, and having a by-pass around the piston and two ports of unequal size opening into the by-pass at one end of the cylinder, an automatic valve for the larger port having an adjustable spring for normally holding it to its seat and a manually-adjustable, non-automatic valve for the smaller port.

8. A speed-governor comprising a cylinder and a piston, and having a by-pass around the piston for the dash-pot fluid and two controlling-valves one of which is seated by spring-pressure and unseated by fluid-pressure.

In testimony whereof I have hereunto subscribed my name this 11th day of August, 1902.

CYRUS ROBINSON.
